CLAIM

The ornamental design for a hand shower, as shown and described.

DESCRIPTION

FIG. 1 is a perspective view of a hand shower, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The dashed or broken lines shown in the environmental structure of the connecting rod for shower articles in which the design is embodied that form no part of the claimed design.

1 Claim, 8 Drawing Sheets
